UNITED STATES PATENT OFFICE.

CHARLES W. HAWKINS, OF BELLPORT, NEW YORK.

REMOVABLE VALVE FOR PUMPS.

1,111,578.

Specification of Letters Patent. Patented Sept. 22, 1914.

Application filed August 6, 1913. Serial No. 783,288.

To all whom it may concern:

Be it known that I, CHARLES W. HAWKINS, a citizen of the United States, and a resident of Bellport, in the county of Suffolk, Long Island, State of New York, have invented a new and Improved Removable Valve for Pumps, of which the following is a full, clear, and exact description.

My invention has for its object to provide 10 a pump with a removable valve, the valve being normally held in place in the core of the pump by bolts, connecting the valve with the core, straps being mounted on the bolts, and engaging the valve, and legs which extend from the core for preventing the pivotal movement of the valve relatively to the core.

Additional objects of the invention will appear in the following complete specification, 20 in which the preferred form of the invention is described.

In the drawings similar characters of reference indicate corresponding parts in both the views, in which—

25 Figure 1 is a sectional elevation showing the core of a pump with a valve member, and provided with my improvement; and Fig. 2 is a sectional side elevation of Fig. 1.

By referring to the drawings, it will be 30 seen that the pump core 5 is provided with a valve member 6, to which is connected the usual valve 7, the valve member 6 having depending portions 8, disposed within the core 5. The core 5 has two legs 9^a, the legs 35 extending down from opposite sides of the core. The depending portions 8 of the valve member 6 are bolted to the core 5, the bolts 9 being used for this purpose. Connected with and carried by these bolts 9 there are 40 straps 10, the straps 10 having terminals 11, through which the bolts 9 are disposed, the central portions 12 of the straps 10 having sides 13, which engage the depending legs 9^a, and sides 14, which engage the bottom 45 of the depending portions 8 of the valve member 6.

It will be noticed that the bolts 9 are disposed in the vertical plane of the legs 9, and that the straps 10 extend in opposite directions, this being best shown in Fig. 2 of the drawings. One of these straps therefore will

5 prevent the pivotal movement of the valve member 6 in one direction relatively to the member 5, and the other strap 10 will prevent the pivotal movement in the other direction of the valve member 6 relatively to the core 5.

Having thus described my invention, I claim as new and desire to secure by Letters Patent:

1. In a device of the character described, a core having a projection, a valve member disposed in and bolted to the core, and a member disposed between the valve member and the projection to prevent the pivotal movement of the valve member relatively to the core.

2. In a device of the character described, a core, a valve member disposed in and bolted to the core, and a member disposed between the valve member and a portion of the core, for preventing the pivotal movement of the valve member relatively to the core.

3. In a device of the character described, a core, a valve member disposed in and bolted to the core, and a member carried by the bolt and disposed between the valve member and a portion of the core, for preventing the pivotal movement of the valve member relatively to the core.

4. In a device of the character described, a core having a leg, a valve member disposed in and pivoted to the core, and a member mounted on the bolt and at one side engaging the valve member and at the other side engaging the leg, to prevent the pivotal movement of the valve member relatively to the core.

5. In a device of the character described, a core having two legs disposed opposite each other, a valve member disposed in the core, the valve member being bolted to the core in the longitudinal planes of the said legs, and members mounted on the bolts and disposed between the valve members and the legs to prevent the pivotal movement of the valve member relatively to the core.

6. In a device of the character described, a core having two legs disposed opposite each other, a valve member disposed in the core, the valve member being bolted to the

core in the longitudinal planes of the said legs, and two straps, one mounted on each of the bolts, the straps extending in opposite directions, and being disposed between the 5 valve member and the legs for the purpose specified.

In testimony whereof I have signed my

name to this specification in the presence of two subscribing witnesses.

CHARLES W. HAWKINS.
